UNITED STATES PATENT OFFICE.

MICHAEL W. McARDLE, OF CHICAGO, ILLINOIS.

SHEEP SHEAR.

Application filed May 12, 1928. Serial No. 277,155.

The purpose of this invention is to provide in a sheep shear an improved construction for adjusting the comb plate in fore-and-aft direction for maintaining the line of cut at 5 desired point on the fixed comb throughout changes in the length of the teeth of the vibrating cutter due to grinding the latter. It consists in the elements and features of construction shown and described as indicated in 10 the claims.

In the drawings:

Figure 1 is a bottom plan view of a sheep shear embodying this invention.

Figure 2 is a vertical fore-and-aft medial 15 section of the same.

Figure 3 is a section at the line 3—3 on Figure 2.

Figure 4 is a top plan view of the fixed comb and cutter detached from the tool.

20 Figure 5 is a dissected perspective view of an operating member concerned in the adjustment of a comb plate for the purpose of the invention.

Figure 6 is a view similar to Figure 1 showing 25 a modified construction.

Figure 7 is a section at the line 7—7 on Figure 6.

Figure 8 is a view similar to Figure 3 showing a modified construction.

30 Figure 9 is a view similar to Figure 4 showing the same modification.

Figure 10 is a view similar to Figure 5 showing the same modification.

In the construction shown in the drawings 35 the sheep shear illustrated comprises a body member, A, upon the under side of which there is mounted adjustably a comb plate, B, which projects forwardly of the body for exposing its upper surface for the lodgment and reciprocation thereon of the vibrating cutter, C, which is actuated for its vibratory movement by the vibrating lever, D, fulcrumed at D¹ and engaging the vibrating cutter in a familiar manner by connections which

40 are familiar and which require no further description here. To adapt the fixed comb and cutter for fore-and-aft adjustment on the body it is held to the under side of the body by screws, E, engaging fore-and-aft

45 extending slots, b, in the fixed comb and cutter, B. For adjusting the fixed comb and cutter in fore-and-aft direction for the purpose stated it has a rearwardly extending stem, B¹, projecting from between the slots, 50 b, and the stem constitutes at its rear part a rack bar having rack teeth, b², formed by

transversely grooving the stem on its upper surface. Immediately above the position of the stem when the comb plate is in place on the body, the body has a recess, A³, and transversely thereof the body is bored for seating the rock shaft comprising members, F, F¹, for carrying and actuating a gear segment member, G, located in the recess A³, and protruding its gear teeth downwardly from said 60 recess for engagement with the teeth of the rack formed as described on the stem of the comb plate.

The recess, A³, is dimensioned to permit the rocking of the shaft for swinging the 70 gear segment through a sufficient arc to cause it to actuate the comb plate in fore-and-aft direction to the maximum distance required for the adjustment mentioned for maintaining the line of cut as desired with respect to 75 the vibrating cutter teeth.

For economy of production and convenience of assemblage of the parts the rock shaft is made in two parts, F and F¹, as mentioned, and said two parts are introduced 80 respectively from the opposite sides of the body having an extended portion toward their inner ends squared as seen at f for engaging square apertures, g, in the radial stems, G¹, of the gear segment into which 85 the squared ends of the rock shaft members are entered from opposite sides of the body, said shaft members having one a centering pin, f², and the other a central bore, f³, to receive the pin and center the shaft members 90 relatively to each other when both are introduced to their working position in the bearing.

For operating the rock shaft the opposite 95 ends of each of the shaft members, F, F¹, are formed for engagement by a suitable key, the construction shown being that said ends are slotted for engagement by a screw driver.

In the form illustrated in Figures 6, 7, 8, 9 and 10 there are provided two separate segment gear members, G^x, G^x, for which laterally separated recesses, A^{3x}, A^{3x}, are formed in the under side of the body, A; and the comb plate has formed in its upper surface at positions corresponding to the recesses, A^{3x}, A^{3x}, 105 laterally separated racks, b^{3x}, b^{3x}; and for mounting and operating the gear segments, G^x, G^x, they are each formed similarly to the segment gear, G, having their radial stems, G¹, provided with square apertures, g. The 110 body, A, is bored transversely to form a reduced journal bearing at a^x, a^x, at the left

hand side (referring to Figure 8), and counter-bored from the right hand side to form a larger diameter being at α' , at the right hand side of the body, and the operating 5 rock shaft, F^{ix} , is unitary, diametered at the right hand end for journalling in the bearing, α' , and at the left hand end for journalling in the lesser bearing, α'' , and squared at an intermediate portion of its length, f'' , 10 for fitting the squared aperture, g , of the segment gear stems.

This form has the advantage that it avoids the liability which may arise in the form shown in the earlier figures, of the comb being 15 slightly more retarded by friction at its guidance on one of the guide and clamp screws, E, than at the other, and thereby turned slightly from the correct fore and aft position of the comb teeth, which would 20 slightly distort the line of cut.

I claim:—

1. In a sheep shear and the like having a body member and a fixed comb plate mounted on the under side of the body member, and a 25

vibrating cutter lodged on the upper side of the fixed comb plate, the latter being adjustable on the body and with respect to the vibrating cutter in fore-and-aft direction, means for adjusting the comb plate comprising 30 a rack bar stem extending rearwardly from the comb plate under the body, having its rack teeth at its upper side; a rock shaft mounted in the body above said rack bar stem, and a segment gear carried by the rock shaft 35 engaging the rack bar, an end of the rock shaft being exposed at the side of the body and adapted for engagement for rocking the shaft to adjust the comb plate.

2. In a sheep shear and the like having a body member and a fixed comb plate mounted on the underside of the body member, and a 40 vibrating cutter lodged on the upper side of the fixed comb plate, the comb plate being adjustable on the body with respect to the vibrating cutter in fore-and-aft direction; means for adjusting the comb plate comprising 45 a rack on the comb plate at the upper side

thereof, the body member having a recess in the under side overhanging said rack; a segment gear mounted in the recess engaging the 50 rack, and a rock shaft journaled in the body engaged with the segment gear, and exteriorly accessible for rocking the shaft.

3. In a sheep shear and the like having a body member and a fixed comb plate mounted on the under side of the body member, and a vibrating cutter lodged on the upper side of the fixed comb plate, the comb plate being adjustable on the body and with respect to the vibrating cutter in fore-and-aft direction, 60 means for adjusting the comb plate comprising an upwardly facing rack on the comb plate, a segment gear meshing with the rack and having axially positioned non-circular apertures; a rock shaft journaled in the body 65 and insertable into its bearings from one side of the body, accessible for operation at the outer end and having an intermediate portion of its length non-circular in cross section fitted to engage the non-circular aperture of 70 the segment gear.

4. In a sheep shear and the like having a body member and a fixed comb plate mounted on the under side of the body member, and a vibrating cutter lodged on the upper side of the fixed comb plate, the comb plate being adjustable on the body and with respect to the vibrating cutter in fore-and-aft direction; means for adjusting the comb plate comprising 75 two upwardly facing racks at opposite sides of a medial fore-and-aft line of the comb plate; segment gears meshing said racks respectively; a rock shaft journaled in the body and extending therethrough from side to side 80 rotatively engaged with both segment gears and accessible and adapted for engagement at both ends for rotating it to operate the racks and adjust the comb plate in fore-and-aft direction.

In testimony whereof, I have hereunto set 90 my hand at Chicago, Illinois, this 9th day of May, 1928.

MICHAEL W. McARDLE.
